Primary Examiner — Khawaja Anwar*Assistant Examiner* — Julice Seung Eun Oum(74) *Attorney, Agent, or Firm* — Derek Fahey, Esq.; The Plus IP Firm, PLLC(57) **CLAIM**

The ornamental design for a golf club elevation tool, as shown and described.

DESCRIPTION

FIG. 1 is a front perspective view of a golf club elevation tool;

FIG. 2 is a front view of the golf club elevation tool;

FIG. 3 is a rear view of the golf club elevation tool;

FIG. 4 is a top view of the golf club elevation tool;

FIG. 5 is a bottom view of the golf club elevation tool;

FIG. 6 is a first side view of the golf club elevation tool;

FIG. 7 is a second side view of the golf club elevation tool;

FIG. 8 is a first side perspective view showing the golf club elevation tool in an operating configuration as affixed to a golf club; and,

FIG. 9 is a front view showing the golf club elevation tool in a storage configuration as affixed to a golf club.

The dashed or broken lines in FIGS. 8 and 9 illustrate a golf club and form no part of the claimed design.

1 Claim, 9 Drawing Sheets
